(57) **CLAIM**

The ornamental design for a fluid dispenser, as shown and described.

DESCRIPTION

FIG. 1 is a perspective view of a fluid dispenser showing our new design;

FIG. 2 is a top plan view thereof;

FIG. 3 is a bottom plan view thereof;

FIG. 4 is a left side view thereof;

FIG. 5 a right side view thereof;

FIG. 6 is a front view thereof; and,

FIG. 7 is a back view thereof.

The broken lines are included for the purpose of illustrating the portions of the fluid dispenser that form no part of the claimed design.

1 Claim, 5 Drawing Sheets# US D717,666 S
